UNITED STATES PATENT OFFICE.

HARRY R. MEYER, OF WILKINSBURG, PENNSYLVANIA, ASSIGNOR TO WESTINGHOUSE ELECTRIC & MANUFACTURING COMPANY, A CORPORATION OF PENNSYLVANIA.

STARTING MECHANISM FOR AUTOMOBILES.

Application filed August 6, 1920. Serial No. 401,738.

To all whom it may concern:

Be it known that I, HARRY R. MEYER, a citizen of the United States, and a resident of Wilkinsburg, in the county of Allegheny and State of Pennsylvania, have invented a new and useful Improvement in Starting Mechanisms for Automobiles, of which the following is a specification.

My invention relates to starting mechanisms for internal-combustion engines and, particularly, to starting mechanisms having motor pinions movable axially into mesh with engine gear wheels.

One object of my invention is to provide a starting mechanism of the above indicated character that shall effect movement of the motor pinion into mesh with the engine gear wheel by means of a cam member which is controlled by an inertia member and will effect demeshing of the motor pinion from the engine gear wheel in a simple and efficient manner upon starting of the engine.

In starting the internal-combustion engine of an automobile by means of an electric motor, considerable trouble is often experienced in satisfactorily meshing the motor pinion with the engine gear wheel without shock or jar and without injury to the teeth of the pinion and the gear wheel.

In the preferred embodiment of my invention, the motor pinion is moved along the armature shaft and is biased, by a spring member, out of mesh with the engine gear wheel. Two cam members and two weighted levers, which are pivotally mounted on the motor shaft, serve to move the motor pinion into mesh with the engine gear wheel upon starting of the motor.

The cam members are biased toward their initial positions by means of spring members, and a latch is provided on one of the cam members for holding the pinion in mesh with the engine gear wheel until the engine is started. A loose connection is provided between the pinion and the armature shaft. Such connection is provided in order to effect the release of such latch upon starting of the internal-combustion engine.

In the accompanying drawing, Figs. 1 and 2 are, respectively, side elevational and plan views of a starting mechanism constructed in accordance with my invention,

and Fig. 3 is a detail view of the connection between the motor pinion and the armature shaft. 55

Referring to the drawing, an engine gear wheel 1 comprises helical teeth 2 cut upon a fly wheel 3 of an engine (not shown). A starting motor 4, of any suitable type, is provided for operating pinion 5 to start the internal-combustion engine. The engine gear wheel and the motor pinion are provided with helical gear teeth for exerting a force tending to pull the pinion into mesh 60 with the gear wheel upon starting of the motor and for exerting a force tending to throw the pinion out of mesh with the gear wheel upon starting of the engine. 65

The pinion 5 is slidably mounted upon a shaft 6 and is connected to such shaft by means of a key member 7. The key member 7 is fitted to a slot formed in the shaft 6 and projects into a slot 8 formed in the pinion 5. The width of the slot 8 is somewhat greater than that of the key member 7 in order to permit a limited movement of rotation of the pinion relative to the shaft. A spring member 10 is mounted upon the shaft 6 between a collar 11 and the pinion 5 for biasing the pinion 5 out of mesh with the engine gear wheel 1. A notch 12 is formed in the pinion 5 for a purpose to be hereinafter set forth. 70

Adjacent to the pinion 5, two cam members 13 and 14 are pivotally mounted, in any suitable manner, upon the armature shaft 6. In the structure shown in the drawing, the two cam members are rotatably mounted on a pin 15 which extends through an enlarged portion 17 of the armature shaft 6. The cam member 14 is provided with a cam surface 16 for engaging the face of the pinion 5, under certain conditions, to force such pinion into mesh with the engine gear wheel. The cam member 13 is provided with a similar cam surface for operating the pinion 5 into mesh with the engine gear wheel. 85 90 95

Two lugs 18 and 19 are mounted, in any suitable manner, upon the portion 17 of the shaft for limiting the movement of the cam members 13 and 14. Two spring members 20 and 21 are provided for biasing the two cam members 13 and 14 into engagement with the lugs 19 and 18. The spring 100 105

members 20 and 21 are connected between pins 22 and 23 which are mounted on the cam members 13 and 14 and a pin 24 which projects through the armature shaft 6. The cam member 14 is provided with a tooth 25 which engages the notch 12 formed in the face of the pinion 5 for holding the pinion 5 in mesh with the engine gear wheel until starting of the engine.

10 Two lever arms 26 and 27 are rigidly connected to the respective cam members 14 and 13 or they may be formed integral with them, as may be desired. The lever arm 26 is provided with a weight 28 and the lever 27 is provided with a similar weight 29. Initially, the spring members 20 and 21 maintain the cam members and the lever arms in the positions shown in the drawing.

15 20 Assuming the elements of the starting mechanism to be in the positions shown in the drawing, in order to start the internal-combustion engine (not shown), the starting motor 4 is energized. Upon operation of the motor 4, the pinion 5 and the cam members and levers attached to the armature shaft 6 are rotated. The inertia of the weighted portions 28 and 29 of the lever arms 26 and 27 tends to prevent movement 25 of such lever arms. Consequently, the lever arms assume positions indicated by dotted lines in Fig. 1 of the drawing. Such movement of the lever arms operates the cam members 13 and 14 to force the pinion 5 30 into mesh with the engine gear wheel 1. When the pinion 5 is in mesh with the engine gear wheel, the tooth 25 enters the notch 12 in the face of the pinion 5 and prevents the spring member 10 from moving the pinion 5 away from the engine gear wheel 1.

35 40 Assuming the shaft 6 and the pinion 5 to be rotating in a counter-clockwise direction, as viewed in Fig. 3 of the drawing, it is apparent that the key 7 engages the left hand wall of the slot 8. Upon starting the engine, the engine gear wheel operates relatively at a greater speed than the pinion 5, and, consequently, the key member 7 is moved from the left-hand side of the slot 8 to the right-hand side of such slot. However, during such movement, the tooth 25 is released and the pinion 5 is forced out of mesh with the engine gear wheel by 45 means of the spring member 10. The spring members 20 and 21 maintain the cam members and the lever members in their initial positions and no movement of the pinion 5 into mesh with the engine gear wheel 1 can again be effected until the motor 4 is stopped.

45 50 Modifications in the mechanism and in the arrangement and location of parts may be made within the spirit and scope of my

invention, and such modifications are intended to be covered by the appended claims.

55 I claim as my invention:—

1. In a starting mechanism, the combination with an engine gear wheel, and a motor pinion, of a spring member for biasing 70 said pinion out of mesh with said gear wheel, a weight member mounted for rotation with said pinion, and a cam member operated by said weight member for forcing the motor pinion into mesh with the engine 75 gear wheel upon rotation of said pinion.

2. In a starting mechanism, the combination with an engine gear wheel, and a motor pinion, of a cam member, and a weight member rotatable with said pinion 80 and having sufficient inertia, when rotated, to operate said cam member to force the pinion into mesh with the engine gear wheel.

3. In a starting mechanism, the combination with an engine gear wheel, and a starting motor having a pinion mounted on the shaft thereof, of two cam members pivotally mounted on the motor shaft adjacent to said pinion, and two weighted lever arms pivotally mounted on said motor shaft 90 and having sufficient inertia, upon starting the motor, to operate said cam members to force the motor pinion into mesh with the engine gear wheel.

4. In a starting mechanism, the combination with an engine gear wheel, a starting motor having a pinion axially movable along the armature shaft, and a loose connection between said pinion and the armature shaft to permit a limited relative rotative movement between said members, of means comprising a cam member for forcing said pinion into mesh with the engine gear wheel, and a latch for maintaining said cam in position to hold said pinion and gear wheel in mesh, said loose connection permitting the demeshing of the pinion and the gear wheel upon starting of the engine.

5. In a starting mechanism, the combination with an engine gear wheel, a starting motor having a pinion movable along the armature shaft, and means for biasing said pinion out of mesh with the engine gear wheel, of means comprising a cam member pivotally mounted on the armature shaft 110 for forcing the pinion into mesh with the engine gear wheel upon starting of the motor.

6. In a starting mechanism, the combination with an engine gear wheel, and a starting motor having a pinion movable along 120 the armature shaft thereof, of means comprising a pivotally mounted cam member for moving said pinion into mesh with the gear wheel, and means for moving said pinion out of mesh with the gear wheel upon starting of the engine.

7. In a starting mechanism, the combination with an engine gear wheel, and a start-

ing motor having a pinion movable along the armature shaft into mesh with said gear wheel, of means comprising a pivotally mounted cam member for moving said pinion into mesh with the gear wheel upon operation of the motor and means comprising a spring member for moving said pinion out of mesh with the gear wheel upon operation of the engine.

- 10 8. In a starting mechanism, the combination with an engine gear wheel, a motor having a pinion rotatable with, and axially movable along, the armature shaft thereof, and a spring member for biasing said pinion out of mesh with the gear wheel, of two cam members pivotally mounted on said armature shaft, two weighted lever

arms connected to said cam members, said lever arms having sufficient inertia, upon starting of the motor, for operating the cam members to force the pinion into mesh with the engine gear wheel, a latch on one of said cam members for holding the pinion in mesh with said gear wheel, auxiliary spring members for biasing the cam members to initial position, and a loose connection between said pinion and the armature shaft for permitting the release of said latch upon starting of the engine.

In testimony whereof, I have hereunto 30 subscribed my name this 30th day of July, 1920.

HARRY R. MEYER.
